LOCOMOTIVE STOKER

Charles J. Surdy, Tuckahoe, N. Y., assignor, by
mesne assignments, to The Standard Stoker
Company, Inc., New York, N. Y., a corporation
of Delaware

Application June 20, 1936, Serial No. 86,281

4 Claims. (Cl. 198—15)

This invention relates to stokers for use in supplying coal from a tender to an inter-coupled locomotive.

The main object of the invention resides in the provision of a locomotive stoker comprising a non-extensible and non-contractile flexible conveyor system having a section mounted on the tender in a manner so that its principal motion is longitudinal with respect thereto.

Specifically, the present invention contemplates the improvement, in structures of the above character, which consists in mounting the speed reduction gearing for the conveyor system rigidly on the tender and providing an extensible and contractile driving connection between the movable conveyor system and the rigidly mounted speed reduction gearing.

Another object of the invention resides in the provision of a flexible conveyor system which is so arranged that, while it may move with respect to the tender, the conveyor system does not act as a support for the conveyor drive gearing, the latter being rigidly mounted on the tender at the rear of said conveyor system and having a telescopic driving connection therewith.

Further objects and advantages will become apparent as the following specification is read in connection with the accompanying drawing, in which

Fig. 1 is a central vertical longitudinal section through adjacent ends of the locomotive and tender, with the improved conveyor system applied thereto, and shown partly in elevation and partly in similar section;

Fig. 2 is a transverse section taken on the line 2—2 of Fig. 1;

Fig. 3 is a section in plan taken on the line 3—3 of Fig. 1; and

Fig. 4 is an enlarged sectional view taken on the line 4—4 of Fig. 3.

On the drawing, the intercoupled locomotive and tender are shown with the locomotive indicated at A, the tender at B, and the coupling connection therebetween at C. This connection may be of any well known construction permitting articulation between the locomotive and the tender, and also providing for the usual amount of longitudinal movement between them.

Fuel is transferred from the fuel bin 10 of the tender B to the firebox of the locomotive boiler 11 by the stoker S which includes a non-extensible and non-contractile flexible conveyor system, comprising a forward section 12, a rearward trough section 13, and an intermediate section 14. The forward conduit section 12 is

rigidly mounted on the locomotive by means of angle bars such as 15 which secure the delivery portion of the conduit section to the boiler back-head 16, and also by the bracket 17.

The lower end of the forward conduit section 12 is formed with a spherical seat 18 to receive the spherical ball member 19 of the intermediate conduit section 14, and constituting therewith between the two conduit sections a universal joint connection 20 disposed on the locomotive A and preferably beneath the cab deck 21. From the joint connection 20, the intermediate conduit section 14 extends rearwardly to the tender B where it is universally connected at 22 to the front end of the trough section 13. This joint connection 22 is formed by the hollow spherical shell 23 of the trough section 13 and the vertically split spherical clamp 24 of the intermediate conduit section 14 fitting over the shell 23. Rotation of the intermediate conduit section 14 is prevented by means of the circular lug 25 on the shell 23 fitting in the groove 26 of the clamp 24. Thus, it will be understood the conduit sections are universally connected and tied together at their adjacent ends, constituting a non-extensible and non-contractile flexible conduit system providing articulation between the conduit section 12 on the locomotive and the conduit section 13 on the tender. It will be observed there is no longitudinal movement between the conduit sections.

Longitudinal movement of the conduit system as a whole with respect to the tender required when the locomotive and the tender traverse a curve, or when coupling up a train of cars, is provided by the novel mounting of the trough section 13 on the tender as now to be described. This trough section 13, positioned beneath the apertured floor 28 of the fuel bin 10 to receive the fuel therefrom, is mounted in the tender for longitudinal movement only with respect thereto, means being provided restraining any appreciable lateral and vertical movement of the trough section 13. Preferably, although not necessarily, the trough section 13 is slidably mounted on or supported from the underframe 29 by the rollers 30 mounted on bearings 31 carried by longitudinally spaced transverse brackets 32, 33, depending from the trough section adjacent opposite ends thereof and arranged with the bearings for the rollers positioned slightly above the underframe whereby the rollers, when mounted on the bearings, rest upon the frames.

The rollers 30 are received in laterally spaced longitudinally extending guideways formed by 55

the parallel channel bars 34, 35. As shown, these channel bars are integral with the underframe 29, although channel bars separable from the frame may be employed. Each channel bar includes an upright leg 36, an inwardly directed top ledge 37 and a bottom or supporting ledge 38, which, as shown, is formed by the top wall of the underframe 29. The rollers 30 are guided in the channel bars, but spaced close to the upper right legs 36 whereby the legs prevent any substantial swinging movement of the trough section 13; likewise, the rollers 30 are fitted closely between the ledges 37 and 38 to prevent any substantial vertical movement of the trough section. However, as shown in Fig. 2, sufficient space between the rollers 30 and channel bars 34, 35 is provided to permit free longitudinal movement of the trough section 13 with respect to the tender. It will be understood that the spacing between the rollers 30 and channel bars 34, 35, as shown in Fig. 2, is exaggerated somewhat in order to secure clarity of illustration.

Fuel is conveyed through the conduit system by a screw conveyor, comprising sections 40, 41 and 42, universally connected at their adjacent ends at 43 and 44, the universal joints 43 and 44 being positioned respectively within the universal connections 20 and 21 of the conduit system. The screw conveyor is driven from its rearward end by means including the drive gearing 45.

During normal operation of the locomotive and tender, the conduit sections 14, 13 rearward of the universal connection 20 are, in effect, pulled along forwardly by the forward conduit section 12. This places a strain on the universal connection 20 and the boiler backhead 16 because the forward conduit section 12 is secured to the latter. In a smaller degree, a strain is also imposed upon the universal joint 23. In order to reduce the strains which would otherwise be imposed on the forward conduit section 12 and the boiler backhead 16, I reduce the weight of conduit system rearward of the universal connection 20.

This result is accomplished by mounting the drive gearing 45 rigidly on the tender at the rear of the trough section 13. Specifically, the drive gearing 45 consists of speed reducing gears 46 which operatively connect the power shaft 47 and the power take-off shaft 48. The gears 46 and associated shafts 47, 48 are carried by the housing 49 and the cover 59. Bolts 51 rigidly secure the housing 49 for the drive gearing 45 to the underframe 29 of the tender. The power shaft 47 is driven from any suitable motor or other prime mover.

Gear housing 49 is so mounted on the tender that the axis of the power take-off shaft 48 is in approximate alignment with the axis of shaft 52. The latter is carried by the trough section 13 in a bearing 53 and has an operative connection at 54 with the conveyor screw section 40. Between the adjacent ends of the screw section 40 and the bearing 53, the shaft 52 carries thrust washers 55.

At its forward end, the power take-off shaft 48 is provided with an enlarged portion 56 having an internal rectangular shaped socket 57. The rearward end of the shaft 52 is provided with an enlargement 58 which engages the socket 57 to form a driving connection between the shafts 48 and 52. As shown, the enlargement 58 is free to slide longitudinally within the socket 57 during longitudinal movement of the trough conduit section 13 and at the same time main-

tains a driving connection between the shafts 48, 52. In order to allow for slight misalignment of the shaft 48, 52 and also for slight vertical and lateral movement of the trough section 13 because of the spacing between rollers 30 and channel bars 34, 35, the outer surfaces of the enlargement 58 of the shaft 52 are curved slightly in longitudinal extent.

From the foregoing, those familiar with railway rolling stock will recognize that my invention provides an improved stoker fired locomotive and tender embodying a very practical, light weight, and efficient non-extensible and non-contractible, flexibly related conduit system secured at one end to the locomotive and at the other comprising a trough section slidably mounted in the tender for movement with respect thereto, which is principally longitudinal. This construction obviates the necessity for telescopic members between the conduit sections, thereby simplifying the conveyor organization. It has the further advantage of maintaining at all times the universal joints of the screw sections within the universal joints of the conduit sections, providing true universal movement between the screw conveyor and the conduit sections, and also avoiding the necessity for longitudinal movement of the screw conveyor in the conduit organization, thereby minimizing the abrasive or cutting action of the screw conveyor. The important feature of mounting drive gearing 45 separately from the conveying system is of special advantage in this construction because it reduces the strains imposed upon parts of the locomotive and upon the forward end section 12.

I claim:

1. In combination with an intercoupled locomotive and tender, the former having a firebox and the latter a fuel bin, a flexible conveyor system for transferring fuel from the tender to the locomotive firebox comprising a conduit supported wholly on the tender for movement longitudinally with respect thereto, means for restraining lateral movement of said conduit with respect to said tender, a conduit mounted on the locomotive and being secured thereto against longitudinal movement, an intermediate conduit establishing communication between the first and second named conduits, said intermediate conduit being inextensible in length and being flexibly related with the first and second named conduits, conveying means in said conduit system including a conveyor screw in the first named conduit, and drive means for operating said conveying means, said drive means including a speed reduction unit rigidly mounted on the tender rearward of and separate from the first named conduit and having a slideable driving connection with said conveyor screw in approximate axial alignment therewith.

2. In combination with an intercoupled locomotive and tender, the former having a firebox and the latter a fuel bin, a flexible conveyor system for transferring fuel from the tender to the locomotive firebox comprising a conduit supported wholly on the tender for movement longitudinally with respect thereto, means for restraining lateral movement of said conduit with respect to said tender, a conduit mounted on the locomotive and being secured thereto against longitudinal movement, an intermediate conduit establishing communication between the first and second named conduits, said intermediate conduit being inextensible in length and being flexibly related with the first and second

- named conduits, conveying means in said conduit system including a conveyor screw in the first named conduit, and drive means for operating said conveying means, said drive means including a speed reduction unit rigidly mounted on the tender rearward of and separate from the first named conduit and having a sliding flexible driving connection with said conveyor screw in approximate axial alignment therewith.
- 5 3. In a locomotive tender, a stoker conduit supported wholly on the tender for longitudinal movement with respect thereto, means for restraining lateral movement of said conduit with respect to said tender, a conveyor screw in said 10 conduit, and drive means for operating said conveyor screw, said drive means including a speed reduction unit rigidly mounted on the tender rearward of and separate from said conduit and having a sliding flexible driving connection with said conveyor screw in approximate axial alignment therewith.
- 10 4. In a locomotive tender, a stoker conduit supported wholly on the tender for longitudinal movement with respect thereto, means for restraining lateral movement of said conduit with respect to said tender, a conveyor screw in said 15 conduit and drive means for operating said conveyor screw, said drive means including a speed reduction unit rigidly mounted on the tender rearward of and separate from said conduit and having a sliding flexible driving connection with said conveyor screw in approximate axial alignment therewith.

CHARLES J. SURDY.
